UNITED STATES PATENT OFFICE.

ARTHUR R. SWANSTROM, OF DULUTH, MINNESOTA.

HORSESHOE.

Application filed December 20, 1923, Serial No. 681,857. Renewed January 30, 1928.

The object of my invention is to provide means for mounting a calk on a horseshoe which will hold it securely and prevent twisting or rotary movement of the calk and the consequent loosening of it in the shoe socket.

A further object is to provide a calk capable of application to either the toe or heel of the shoe and capable of adjustment to compensate for slight variations in the relative position of the sockets in the shoe wherein the calk is mounted.

Other objects of the invention will appear from the following detailed description.

The invention consists generally in various constructions and combinations all as hereinafter described and particularly pointed out in the claims.

In the accompanying drawings forming part of this specification,

20 Fig. 1 is a perspective view of a horseshoe with my invention applied thereto;

Fig. 2 is a plan view of the calk removed from the shoe;

25 Fig. 3 is a side view of a modified construction;

Fig. 4 is a similar view of another modification;

Fig. 5 is a plan view of Fig. 4;

30 Fig. 6 is a plan view of another modification;

Fig. 7 is a side view showing the reverse of the modified construction of Fig. 5; and

Fig. 8 is a view showing the calk blade with toothed or serrated edge.

35 In the drawing, 2 represents a horseshoe of ordinary construction having sockets 3 arranged in pairs in the toe and heel of the shoe. These sockets are tapered slightly to receive the correspondingly tapered studs 4

40 which are adapted to fit snugly therein. A blade 5 is formed on the upper ends of the studs and has a straight outer face 6 and an inner face 7 that is preferably inclined or tapered. The blade bridges the space between the studs and is preferably mounted

45 thereon in advance of the longitudinal axes of the studs as indicated in Fig. 1, and as there shown the blade is preferably curved from end to end so that the edge thereof for contact with the ground will follow substantially the arc of a circle. The purpose of having this blade curved slightly is to allow the blacksmith to conveniently increase the distance between the studs when it is necessary 50 to do so in fitting the studs into the sockets

of the shoe. Evidently, if the blade were straight and the blacksmith found it necessary to separate the studs a greater distance he would have to draw the plate slightly by heating it or in some other way, while the 60 slight curve in the plate permits the distance between the studs to be instantly increased by striking the blade with a hammer and decreasing slightly the degree of curvature. In the same way, if the blacksmith wishes to 65 draw the studs together he can do so by bending the blade in the other direction to increase the degree of curvature. The straightening of the blade will increase the distance between the studs as indicated by dotted lines 70 in Fig. 2. Evidently with the blade supported at both ends on the studs it will be impossible to loosen the studs by a twisting rotary strain on the blade, as lateral pressure on one end of the blade and its supporting 75 stud will tend to force the other stud more firmly against the wall of the socket. When only one socket and stud is provided for a shoe calk any twisting or rotary strain to which the calk is frequently subjected will 80 tend to loosen it and will soon allow it to drop out of the shoe.

In Fig. 3, I have shown a modified construction which consists in providing a transverse recess 8 preferably near the middle of the plate and extending to a point sufficiently near its lower edge to allow it to bend vertically or in the plane of the plate as well as transversely thereof, thus further adapting the device for conveniently and firmly fitting 85 the tapered studs into the sockets of the shoe.

In Fig. 4, the middle portion of the plate is cut away as indicated at 9 and a bridge 10, preferably arched as shown, connects the opposite lower portions of the ends of the plate. 90

Fig. 5 illustrates how this bridge may be cut away as indicated at 11 to provide less metal at this point and facilitate bending to adjust the studs to enter the sockets of the shoe.

100 In Fig. 6, a bridge 12 is shown curved outwardly to project beyond the plane of the plate having, however, substantially the same function as the bridges shown in the other views.

105 In Fig. 7, the bridge 10^a is curved downwardly in the opposite direction from the curvature of the arch shown in Fig. 4. These bridges all allow for transverse and vertical movement of one end of the plate with re- 110

spect to the other to allow accurate fitting of the studs in the sockets, and at the same time the bridges hold the plate ends against rotary or twisting movement which would allow the studs to turn in the sockets and become loosened by such movement.

In Fig. 8, a solid plate is shown having a series of indentations or notches 13 forming teeth or serrations on the tread edge of the plate. These teeth may be provided in the calk plate when the shoe is to be used on a slippery road or pavement for the purpose of allowing a better grip on the roadway.

I have shown the calk applied to the toe of the shoe; but similar sockets 3 are formed in the heel, and the same type of calk mounted on the tapered studs in substantially the same way may be used at the heel of the shoe as well as at the toe.

20 I have shown and described various forms of a bridge connecting the ends of the calk plate, but I do not wish to limit myself to any of these structures as various other ways may be devised for weakening the middle portion 25 of the blade to allow for the relative adjustment of the ends of the blades and the studs and still be within the scope of my invention.

The forms of the invention shown in Figs. 3, 4, 5, 6, and 7, are particularly valuable in that 30 the ground-engaging surface of the blade is broken, and provides corners and edges 17 as "bites" or "grips" arranged intermediately of the ends of the blade. This feature of the invention is advantageous for one reason that 35 the corners 16 are thrown forward during adjustment at the weakened portion to increase the gripping action of the blade when in use. Another advantage is the arrangement of the weakened portion at the forward side of the calk. This is true for the reason that if we 40 imagine a line drawn through the axes of the calk the points 16 and 17 lie forwardly of the axes, and a slight forward adjustment of the middle portion obtains a greater relative adjusting movement between the studs. This 45 feature which provides for a greater adjusting movement of the studs, as the result of a relatively small bending movement at the weakened portion is a valuable feature. The "bites" 16—17, in conjunction with the "bites" 50 20 at the terminal portions of the blade improve the ground-gripping action of the blade. The device as shown in Fig. 8 also provides "bites" 21 which also assist in gripping. However, it will be noted that as shown 55 in Figs. 4, 5, 6, and 7, the "bites" are provided as the result of weakening the central portion. It will be understood that whatever 60 the area of the weakened portion, if this area is less than the vertical dimension of the blade or if its thickness is less than the thickness of the blade, these corners 16 and edges 17 will be provided at the ground-engaging side.

It will be noted that the thickness of the 65 weakened portions is, in Figs. 4, 5, 6, and 7,

shown as less than the thickness of the blade 5. This permits an annealing operation to be performed without affecting those portions of the blade adjacent the weakened portion, because the cross-sectional area at the point of connection is reduced to prevent that amount of heat conduction to the other parts, which would reduce the "temper", and therefore soften the unweakened lateral portions of the blade.

70 I claim as my invention:

1. The combination with a horseshoe having sockets therein, of a calk comprising studs to fit snugly within said sockets, a blade supported by said studs and having a transverse 80 opening therein extending partially through said blade, and forming a bridge across said opening and connecting the end portions of said blade, said bridge allowing said blade to be conveniently bent to register said studs with their respective sockets.

2. The combination with a horseshoe having a series of sockets therein, of a calk comprising studs to fit said sockets, and a blade mounted on said studs having a weakened area between its ends to allow bending of the blade perpendicularly of the shoe.

3. A calk having studs connected by a blade, said blade slotted intermediately to permit bending adjustments in direction of the axes of the studs.

4. A calk having tapering studs connected by a blade, said blade slotted intermediately and bowed to permit bending adjustments both in direction of taper of the studs, and at 100 angles transversely to the direction of taper.

5. A calk having studs connected by a blade, said blade having a weakened area formed by slotting and by reducing the thickness, respectively in directions at angles to one another.

6. A calk having studs connected by a blade, said blade having a weakened area formed by slotting in two directions respectively inwardly from the ground-engaging edge and inwardly from the rear face.

7. A calk having studs connected by a blade, said blade having a weakened area formed by slotting in two directions respectively inwardly from the ground-engaging edge and inwardly from the rear face, the said weakened portion lying forwardly of a line drawn through the axes of the studs.

8. The combination with a horseshoe having a series of sockets therein, of a calk providing studs to fit said sockets, and a blade on said studs and having a weakened area intermediately of the studs to allow bending of the blade, the said area being formed by slotting the blade in two directions, and at a point intermediate the studs.

9. The combination with a horseshoe having a series of sockets therein, of a calk providing studs to fit said sockets, and a blade on said studs having a weakened area intermediately of the studs, the weakened area being 130

formed by reducing the cross-sectional area in two directions substantially perpendicular to one another.

10. A calk having studs connected by a blade, said blade having two sections, connected by an intermediate section having its area reduced in two directions to form a weakened area of substantially less cross-section than that of the connected portions.
- 10 11. A calk having studs connected by a blade, said blade having a weakened area formed by slotting in two directions to substantially decrease the cross-section of the connecting portion.
- 15 12. A calk having studs connected by a blade, having a reduced portion intermediate of the studs, the cross-sectional area of which is less than both the thickness and width of the blade, whereby an annealing 20 operation can be performed to make said connecting portion bendable without affecting the temper of the adjacent portions.

13. A calk having studs connected by a blade, the said blade comprising two lateral

sections, connected by an intermediate section 25 which is of substantially less cross-sectional area in two directions, than that of the elements which it connects.

14. A calk having studs connected by a blade, said blade having a weakened area 30 formed by reducing the thickness in directions substantially perpendicular to one another.

15. A pair of spurs each having a stud perpendicular to its base, an element connecting the spurs in direction transversely to the stud 35 axes and only at a point adjacent the bases of the spurs, the cross-sectional area of the connecting element being substantially less than that of the spurs, whereby compensatory 40 movements of the studs to fit an opening may be had although one stud may be driven farther into an opening than the other, and whereby under the latter condition the studs will not work out of their openings during 45 use.

In witness whereof, I have hereunto set my hand this 10th day of December 1923.

ARTHUR R. SWANSTROM.
